UNITED STATES PATENT OFFICE.

ARTHUR M. BURNHAM, OF GARDINER, MAINE, ASSIGNOR OF ONE-HALF TO
LEONARD MOODY, OF BROOKLYN, NEW YORK.

MOP-WRINGER.

SPECIFICATION forming part of Letters Patent No. 549,104, dated November 5, 1895.

Application filed February 20, 1895. Serial No. 539,082. (No model.)

To all whom it may concern:

Be it known that I, ARTHUR M. BURNHAM, a resident of Gardiner, in the county of Kennebec and State of Maine, have invented certain new and useful Improvements in Mop-Wringers; and I do hereby declare the following to be a full, clear, and exact description of the invention, such as will enable others skilled in the art to which it appertains to make and use the same.

My invention relates to an improvement in mop-wringers, and more particularly to such as are adapted to squeeze the mop, one object of the invention being to so construct a mop-wringer that it will not injuriously affect the mop, as is the case with mop-wringers employing rollers.

A further object is to so construct devices for wringing a mop that the compressor will be made to travel the major portion of its movement with the expenditure of a comparatively small amount of treadle-power and exert a maximum amount of pressure on the mop when the movement of the treadle shall have been nearly completed.

A further object is to provide means whereby a mop-wringer can be adjusted for different-sized mops.

A further object is to produce a mop-wringer which shall be simple in construction, comparatively cheap to manufacture, and which shall be effectual in all respects in the performance of its functions.

With these objects in view the invention consists in certain novel features of construction and combinations and arrangements of parts, as hereinafter set forth, and pointed out in the claims.

In the accompanying drawings, Figure 1 is a side view. Fig. 2 is a vertical longitudinal sectional view. Fig. 3 is a plan view. Fig. 4 is a view of a modification.

A represents a pail, preferably made angular in form with the upper edges of the sides rounded. Within the pail A a curved compressor-plate B, having a number of perforations *a*, is pivotally supported by means of a shaft *l*, mounted at its respective ends in the sides of the pail, the pivoted end of said plate being curved, as at *b*, concentric with the shaft *l*. The compressor-plate B is adapted

to act in conjunction with a fixed perforated plate C and with a sliding spring-sustained plate D to press or squeeze the water from a mop disposed between them, the shank of 55 said mop being made of such form as to enter a slot *c*, so as to permit the compressor-plate to engage the sliding plate and contract the space occupied by the mop. The plate C is secured between the sides of the pail, so that 60 its lower edge will be disposed in close proximity to the curved portion *b* of the compressor B. The sliding plate D is made slightly curved and adapted to slide past and in close proximity to the upper edge of the 65 fixed plate C. A bar *d* is secured transversely to the plate D near its upper edge and projects beyond the edges of said plate to produce lugs *e*, which enter curved elongated slots *f* in the sides of the pail, and any water 70 which may find its way through these slots will be caught by small troughs *g*, secured to the sides of the pail, and by said troughs be reconveyed to the interior of the pail through the slots. The sliding plate D is also guided 75 in its movements by means of curved guides *h*, secured to the sides of the pail. Said sliding plate is maintained in its normal position by means of a spring *D'*, secured at one end to the bottom of the plate and at the other 80 end to the upper edge of the pail.

The arms *i* of a treadle *j* are pivotally connected to the pail and between their ends are bent and provided with journals *k* for the reception of rollers *k'*. The shaft *l*, to which 85 the compressor-plate is secured, projects at both ends beyond the sides of the pail and at its extremities is provided with fixed arms *m*, made at their ends with segments *m'*, having teeth *m*².

Between the arms *m* and the pail levers *n* are loosely mounted on the shaft *l*, and each lever is provided with a perforated lug *o* for the reception of a thumb-screw *p*, by which to secure a block *p'* thereto, said block having teeth *p*² to engage the teeth *m*² on the segments *m'*.

If desired, the teeth *m*² of the segments may be made in the form of ratchet-teeth and the toothed blocks displaced by dogs *p*⁵, 100 maintained normally in contact with the teeth by means of a spring *p*⁶, as shown in

Fig. 4. The levers *n* are curved and constitute a track on which the rollers *k'* run, so that when the treadle is depressed the levers *n* will be moved down and the shaft *l* turned, carrying the compressor-plate *B* upwardly and compressing the mop between it and the plates *C D*, the water in the mop escaping through the perforations in said plates. A continued pressure on the treadle will cause the compressor to bear on the sliding plate *D* with such pressure as to cause the latter to move downwardly, thus contracting the space occupied by the mop and thoroughly wringing the water from the same. As soon as the treadle is released, the spring *D'* will return the sliding plate *D* to its normal position, and the compressor-plate *B* will fall by its own weight to its normal position in the bottom of the pail.

It will be observed that the levers *n* are so made that in proximity to their inner ends, where they are connected to the shaft *l*, their curvature is somewhat abrupt, as at *p⁸*, and that the curvature from the part *p⁸* toward the free ends of the levers is of a less degree. It will be seen, therefore, that when the treadle is first depressed the compressor-plate will be moved quickly (and with little exertion on the part of the operator) toward the plates *C D*, and that when the resistance offered by the mop is encountered the rollers on the treadle-arms will be on the long curve *p⁹* of the lever and some distance from the fulcrum of the latter. As the pressure on the treadle continues the connection between the treadle and levers *n* moves away from the fulcrum of the latter, and the leverage on the compressor-plate increases until the maximum amount of pressure on the mop is attained, when the treadle will be in proximity to the base of the pail.

In the use of mop-wringers of the class to which my invention relates, as they have heretofore been constructed, it has been necessary to withdraw the mop from the water in the pail and then place it in the wringing or squeezing device. With my improved construction it is not necessary to withdraw the mop, but merely to raise it slightly, and thus the inconvenience of wholly withdrawing the mop is avoided.

By connecting the levers *n* with the shaft *l*, through the medium of the adjustable arms *m*, the device can be readily adjusted for mops of different sizes. The adjustment should be so made relatively to the size of the mop that the treadle can be depressed to the base of the pail, so as to derive the benefit of the fullest amount of leverage on the compressor.

My improvements are very simple in construction, comparatively cheap to manufacture, and effectual in all respects in the performance of their functions.

Various slight changes might be made in the details of construction of my invention without departing from the spirit thereof or

limiting its scope, and hence I do not wish to limit myself to the precise details of construction herein set forth; but,

Having fully described my invention, what I claim as new, and desire to secure by Letters Patent, is—

1. In a mop wringer, the combination with a pail, of a pivotally supported compressor plate, a fixed plate cooperating therewith, and a sliding compressor plate cooperating with said first-mentioned plates, substantially as set forth.

2. In a mop wringer, the combination with a pail, of a pivotally supported compressor plate, a sliding compressor plate cooperating therewith, and a spring constructed and adapted to return the sliding plate to its normal position, substantially as set forth.

3. In a mop wringer, the combination with a pail, of a pivotally supported compressor plate, a rigid plate, and a sliding plate cooperating therewith, a treadle and a lever connected with the pivoted compressor plate and cooperating with said treadle, substantially as set forth.

4. In a mop wringer, the combination with a pail, of a pivoted compressor plate, a sliding compressor plate, and means for moving the pivoted plate causing it to engage the sliding plate and contract the space between said plates, substantially as set forth.

5. In a mop wringer, the combination with a pail, of a pivoted compressor plate a rigid plate cooperating therewith, a sliding plate, a treadle and curved levers connected with the pivoted compressor plate and adapted to be engaged by the treadle arms, substantially as set forth.

6. In a mop wringer, the combination with a pail, of two cooperating compressor plates and a sliding plate therein, a treadle, and devices between said treadle and one of the compressor plates whereby to cause the movement of one of said plates toward the other with increasing force toward the end of the throw of the treadle, substantially as set forth.

7. In a mop wringer, the combination with a pail, of compressor plates therein, one of said plates being pivotally supported, a treadle, a lever connected with the pivoted compressor plate, and a roller carried by the treadle and adapted to move on and operate said lever to move the pivoted compressor plate as the treadle is depressed, substantially as set forth.

8. In a mop wringer, the combination with a pail, of compressor plates therein, one of said compressor plates being pivotally supported, a treadle, a lever mounted on the shaft of the pivoted compressor plate and adapted to be engaged by the treadle and means for adjustably securing said lever to the shaft of said pivoted compressor plate, substantially as set forth.

9. In a mop wringer, the combination with a pail, of compressor plates therein, one of said compressor plates being pivotally supported, a treadle connected to the shaft of said

- pivoted plate, a pin projecting from the arm of the treadle and a roller mounted on said pin and adapted to run on said lever, substantially as set forth.
- 5 10. In a mop wringer, the combination with a pail and a pivoted compressor plate therein, of an arm secured to the shaft of said compressor plate and provided with a series of teeth, a lever loosely mounted on said shaft, 10 a securing device connected to said lever and adapted to engage said teeth, and a treadle adapted to engage said lever, substantially as set forth.
11. In a mop wringer, the combination with 15 a pail having slots therein and a pivoted compressor plate in said pail, of a sliding compressor plate adapted to cooperate with the pivoted plate, lugs projecting from said sliding plate through the slots in the pail, and a 20 spring for returning the sliding plate to its normal position, substantially as set forth.
12. In a mop wringer, the combination with
- a pail having slots therein and a pivoted compressor plate, of a sliding compressor plate co-operating with the pivoted compressor plate, 25 lugs on the sliding plate projecting through said perforations, and troughs at the lower ends of said slots, substantially as set forth.
13. In a mop wringer, the combination with a pail, of cooperating compressor plates therein, one of said plates being pivotally supported and having a slot therein for the reception of the shank of a mop and the other compressor plate being constructed and adapted 30 to have a sliding movement, substantially as 35 set forth.

In testimony whereof I have signed this specification in the presence of two subscribing witnesses.
